TAPE DISPENSER

Paul Van Cleef and Frank Chonacki, Chicago, Ill., assignors, by mesne assignments, to Johns-Manville Corporation, New York, N. Y., a corporation of New York

Application June 20, 1946, Serial No. 677,998

5 Claims. (Cl. 164—84.5)

1

This invention relates in general to tape dispensers. More particularly, the invention relates to that known type of dispenser which is expressly designed and adapted for use in handling permanently tacky or so-called pressure sensitive adhesive tape, and comprises as its principal components or parts: (1) a frame embodying a pair of parallel laterally spaced upstanding sides, together with means for rotatably supporting the roll of tape between the sides, and (2) a platform which is located or positioned adjacent the sides of the frame and in alignment with the space between the frame sides, and has adjacent its outer margin a cutting edge for cutting the tape into lengths as it is unwound from the roll.

When it is desired, in connection with use of a tape dispenser of the aforementioned type, to sever a length of tape from the roll, the outer end of the tape is pulled outwards a distance corresponding to the length of tape that is desired, and then the inner end of the pulled length is brought to the end of the platform, and into adhesively connected relation with the platform, and is severed by pulling it downwards so that it is cut by the cutting edge adjacent the outer margin of the platform.

When it is desired to cut another length from the roll, the outer end of the tape is removed from the platform and then pulled outwards, the last mentioned operation being followed by the steps or operations heretofore described.

In practice, it has been found that the work or effort incident to manual stripping or removal of the free or outer end of the tape from the platform each time a length of tape is severed from the roll, renders use of a dispenser of the type under consideration objectionable or difficult.

Furthermore, the constant adhesion of the adhesive face of the tape to the platform, and the subsequent removal thereof during dispensing or paying out of the tape, causes the upper surface of the platform to become sticky. This is not only objectionable, but is also undesirable for many reasons, as such sticky surface is exposed, and foreign particles will adhere thereto.

It is one of the objects of the present invention to overcome these difficulties and objections by providing a tape dispenser in which the adhesive face or surface of the tape will be maintained out of contact with the platform and the cutting margin or edge thereof, and in which the cut or leading end of the stock from which a length of the tape has been severed, will automatically assume a position to be readily grasped

2

by the operator for drawing out another length of the tape.

Another object is to provide improved means for facilitating the grasping and drawing out from the roll of additional lengths of the tape to be severed.

10 A further object is to provide in a tape dispenser of this character, improved means for supporting or sustaining in position to be grasped by the operator, the free end of the stock or tape from which the length has been severed.

15 A further object is to provide in a tape dispenser of this type, improved means for guiding the tape beneath the platform, and for maintaining the top or exposed surface of the platform and cutting edge against being contacted by the sticky surface of the tape.

20 A still further object is to provide an improved dispenser of this character, which is simple in construction, and effectively and efficiently serves its intended purpose.

25 To the attainment of these ends, and the accomplishment of other new and useful objects as will appear, the invention consists in the features of novelty in substantially the construction, combination and arrangement of the several parts, hereinafter more fully described and claimed, and shown in the accompanying drawings illustrating this invention, in which

30 Fig. 1 is a side elevation of a tape dispenser, constructed in accordance with the principles of this invention;

Fig. 2 is a top plan view;

35 Fig. 3 is an enlarged fragmentary section taken on the line 3—3, Fig. 2;

Fig. 4 is a similar section of a modified form of the invention; and

Fig. 5 is a perspective of the guiding roll and the cutting means for the tape.

40 Referring more particularly to the drawings, the numeral 10 designates a supporting base provided with spaced upright side walls 11 which may be of any desired size and configuration, and constructed of any suitable material. The

45 numeral 12 designates a roll of permanently tacky pressure sensitive adhesive tape, and this roll is provided with an axle 13, the ends of which are adapted to enter open top grooves 14 in the inner faces of the side walls, the roll may be 50 readily inserted in place and also removed.

55 At the forward end of the side walls 11 and in alignment with the roll is a horizontal platform or ledge 15 which may be of any desired size and configuration. Preferably the ledge is fixedly secured in place by means of horizontal fasten-

ing bolts or screws 16 which extend through holes in depending legs at the ends of the ledge and also into screw threaded sockets in the front portions of the side walls 11. The forward edge of the ledge is sharpened or otherwise formed to provide a cutting edge 17, the ledge and cutting edge being so positioned that the tape 18 that is being delivered from the roll 12 may pass thereunder. In order to guide the tape under the ledge with its cutting edge there is provided a roller 19 which is engaged by the tacky adhesive face of the tape.

In operation, the forward end of the tape passes over the guiding roller 19 with the tacky face facing downwards and in engagement with the roller, and is directed beneath the ledge 15 and also the cutting edge 17, as shown clearly in Fig. 3, so that the forward end 20 of the tape will be suspended in such a position that the operator may readily grasp the same to draw more of the tape from the roll. Inasmuch as the tacky surface of the tape will face downwardly and away from the ledge, as shown in Fig. 3, it may be readily grasped by the operator. If desired, and in order to draw more of the tape from the roll, the operator may engage the lower surface of the forward end of the tape, and press the non-tacky surface of the tape against the lower face of the ledge 15 and cutting edge 17. This will cause the tape to adhere to the finger of the operator, and he may then lower his finger, with the tape adhering thereto, into a position to be grasped with the thumb and fore-finger. When a sufficient quantity of the tape has been drawn off the roll, the forward portion thereof may be severed by swinging the tape upwards and at the same time drawing it transversely across the cutting edge 17, as shown in Figs. 1 and 2.

It sometimes happens that the tape is very thin and flexible and hence tends to drop and contact a part of the framework, so that it will not be in a convenient position to be grasped by the operator. In order to overcome this difficulty, when a thin tape is employed, there may be provided an additional roller 21, which is rotatably supported in any suitable manner, such as by means of brackets 22, arranged beneath the ledge 15 and sufficiently close to the lower face thereof so as to support the forward end 23 of the tape in a position to be grasped by the operator, as shown in Fig. 4. The roller 21 extends horizontally and is so positioned that the end of the tape when hanging from the roller is spaced in front of the front wall of the framework that embodies the base 10 and the side walls 11.

If the additional roller 21 is employed the tape may be drawn from the roll in the same manner as described in connection with the form of the invention that is shown in Fig. 3.

In order to permit the user to observe the position of the free end of the tape 18 beneath the ledge 15 and the cutting edge 17 and thus facilitate grasping such end, a portion 24 of the ledge 15, or the entire ledge, may be made of transparent material. In lieu of the transparent portion 24, the ledge may be cut out to provide a sight opening therethrough.

Means may also be provided for determining or measuring the length of tape dispensed, and to that end a measuring device such as a ruler 25 may be suitably mounted so as to swing about a vertical pivot 26 in order that it may be swung into a position to extend lengthwise of the tape that is being paid out, and also swung in the opposite direction into an inoperative position

wherein it extends longitudinally across the ledge 15 and does not interfere with the tape being cut or torn off. As shown in Figure 4, the pivot 26 extends through aligned holes in one end of the ruler and one end of the ledge.

While the preferred forms of the invention have been herein shown and described, it is to be understood that various changes may be made in the details of construction, and in the combination and arrangement of the several parts, within the scope of the claims, without departing from the spirit of the invention.

What is claimed as new is:

1. A device adapted to dispense strips from material with a coating of permanently tacky pressure sensitive adhesive on one face thereof, and embodying means for holding a supply of the material, a stationary cutting element provided with a cutting edge at its front and disposed in front of the holding means, a pair of freely rotatable rollers disposed in the rear of the cutting edge of said cutting element, said rollers being spaced one in advance of the other, one of said rollers operating to guide the material under said

20 cutting element with the non-tacky surface of the material adjacent the cutting element, the other of said rollers serving to support the free end of the material in position to be grasped by the operator, the material contacting surface of said other roller being disposed below the material contacting surface of the guiding roller.

2. A device adapted to dispense strips from a roll of material with a coating of permanently tacky pressure sensitive adhesive on one face

35 thereof, and embodying means for rotatably holding the roll, a ledge positioned in alignment with the roll and having a forward cutting edge, means for guiding the material beneath said ledge with the non-tacky surface adjacent said

40 ledge, said means being so disposed with respect to the said cutting edge that after a strip is severed by the cutting edge the tacky face of the one end of the next following portion of the material may be engaged by the finger of the operator and

45 pressed against the bottom of said ledge in order to cause the material to adhere to the finger and thus facilitates drawing of the material from the roll, said means embodying a roller mounted for free rotation and arranged so that it is engaged

50 by the tacky face of the material, and a second roller mounted for free rotation, spaced in advance of the first roller and in a lower horizontal plane, positioned beneath and directly rearwards of said cutting edge, and adapted to serve as a

55 support from which the free end of the material depends prior to being gripped by the operator in connection with the next strip severing operation.

3. A device adapted for use in dispensing a roll of tape with a coating of permanently tacky

60 pressure sensitive adhesive on one face thereof, and embodying means for rotatably supporting the roll, a ledge positioned in alignment with the roll and having a tape-cutting instrumentality associated therewith and located forwards there-

65 of, guide means to direct the tape beneath said ledge and so that the non-tacky face of the tape is in contact with the bottom surface of the ledge, and a sight opening formed in the said ledge and adapted to permit the user of the device to see

70 the portion of the tape that is below the ledge.

4. A device adapted for use in dispensing a roll of tape of the type that has on the inner side face a coating of permanently tacky pressure sensitive adhesive, and comprising a framework em-

75 bodying a front wall and a pair of laterally

spaced side walls extending rearwards from the side margins of the front wall, means associated with the framework for supporting the roll between the side walls thereof, an elongated, horizontally positioned leg located in front of, and slightly above, the upper margin of the framework front wall, provided at the front thereof with a cutting edge, and having at its ends a pair of depending legs connected fixedly to said side margins of the front wall of the framework, and a horizontal, small sized, freely rotatable roller positioned between the upper corners of the framework side walls and directly behind the ledge, adapted to have the tape drawn over it with the adhesive coating facing downwards and engaging it, and serving to guide and direct the free end of the tape so that it extends through the space between the upper portion of the legs and also under the ledge and has its untacky outer side face opposite the under surface of the ledge.

5. A device adapted for use in dispensing a roll of tape of the type that has on the inner side face a coating of permanently tacky pressure sensitive adhesive, and comprising a framework embodying a front wall and a pair of laterally spaced side walls extending rearwards from the side margins of the front wall, means associated with the framework for supporting the roll between the side walls thereof, an elongated, horizontally positioned ledge located in front of, and slightly above, the upper margin of the framework front wall, provided at the front thereof with a cutting edge, and having at its ends a pair of depending legs connected fixedly to said side margins of the front wall of the framework, a horizontal, small sized, freely rotatable roller, positioned between the upper corners of the frame-

work side walls and directly behind the ledge, adapted to have the tape drawn over it with the adhesive coating facing downwards and engaging it, and serving to guide and direct the free end of the tape so that it extends through the space between the upper portions of the legs and also under the ledge and has its untacky outer side facing opposite the under surface of the ledge, and a second horizontal, small sized, freely rotatable roller positioned in advance of the first mentioned roller and in a lower horizontal plane, disposed directly beneath the rear portion of the ledge and behind said cutting edge, and adapted to form a support whereby, prior to the next following tape severing operation, the free end of the tape is supported in a depending manner in front of, and in spaced relation with, the front wall of the framework.
